APPARATUS FOR ADJUSTING RESISTORS

Henry G. Richter, Westfield, N. J.

Application February 27, 1935, Serial No. 8,433

9 Claims. (Cl. 51—105)

This invention relates to apparatus for use in the manufacture of resistors, and more particularly for adjusting the resistance value of film type resistors.

5 A problem of long standing in the manufacture of resistors has been to make the resistors with uniformly correct resistance value. Many manufacturers rely upon subsequent calibration, that is, a large number of resistance elements (herein-
10 after conveniently referred to as resistors) are made and are subsequently subjected to resistance measurement and classified in groups according to the resistance reading obtained. One obvious disadvantage of this procedure is that only some of the resistors are of desired measurement, and in the absence of companion orders for resistors of different measurement, the others must be discarded or made over. One object of my invention is to obviate the foregoing difficulty.
15 Some suggestion to the same end has heretofore been made with a view to removing some of the resistance surface, thereby raising the resistance value. This procedure presupposes that the resistors initially have too low a value. If the resistors are all purposely made too low in value, excessive treatment is required to bring the same up to desired value. Furthermore, the operation of raising the resistance value is a sensitive one, and frequently the treatment goes further than desired, resulting in an element having a measurement too high and not susceptible of additional treatment. In accordance with a further object of my invention, I provide apparatus adapted to either raise or lower the resistance value at will. I further combine with the apparatus an appropriate resistance meter or ohm meter, and each element placed in the apparatus is readily subjected to any necessary raising or lowering of resistance value until it is adjusted to precisely the desired reading. The resulting elements have an accurately determined measurement instead of merely falling into some classification or range of measurement. Furthermore, the initial manufacture of the elements is directed 45 or aimed at the production of the desired resistance value, so that the resistors center about the desired value as a mean, many batches requiring but little treatment and the average amount of adjustment being reduced to a minimum.
50 Further objects of my invention center about the treatment of elements intended for use in variable resistance units. One problem raised in connection with such units is due to the effect of sliding of the contact shoe over the resistance surface. I find that there is a rapid change in re-

sistance value during the first few hundred oscillations of the contact shoe on the resistance surface, but that thereafter the change in resistance slows down and soon becomes negligible. One object of my invention is to remedy this resistance variation which takes place during the early life of the unit, and to this end I combine with the aforementioned apparatus appropriate means for burnishing the surface of the unit in simulation of the action of the contact shoe, in consequence of which the resistance reading obtained when the unit is adjusted corresponds to the stable value which ordinarily would be reached only after the first period of use and which would differ from the calibration value. This extra 10 burnishing step is optional, for the regular treatment for adjusting the resistance value itself includes considerable rubbing and burnishing.

Another difficulty arises in connection with variable resistance units because these units are frequently stepped or "tapered" in value. This may necessitate separate treatment or adjustment of different parts of the resistor, and another object of my invention is to provide apparatus elements which make possible separate selective treatment of any section of the resistor as well as uniform treatment of the entire resistor.

Further objects of my invention are to devise apparatus to which the resistors may be applied in rapid succession and in which they may be treated conveniently and expeditiously by unskilled labor, all with a view to minimizing the cost of the resistors which are sold under highly competitive conditions.

To the accomplishment of the foregoing and other objects which will hereinafter appear, my invention resides in the apparatus elements for adjusting resistors, and their relation one to the other, as are hereinafter more particularly described in the specification and sought to be defined in the claims. The specification is accompanied by drawings, in which:

Fig. 1 is a front elevation of a preferred form of apparatus embodying features of my invention;

Fig. 2 is a section taken in the plane of the line 2—2 of Fig. 1;

Fig. 3 is a horizontal section taken in the plane of the line 3—3 of Fig. 1;

Fig. 4 is a section taken in elevation in the plane of the line 4—4 of Fig. 2;

Fig. 5 is a plan view in the plane of the line 5—5 of Fig. 4;

Fig. 6 shows in perspective a type of resistor

which the present form of my apparatus is best adapted to handle;

Fig. 7 is a schematic wiring diagram for the apparatus;

5 Fig. 8 is a side elevation of a portion of the apparatus modified for automatic or power oscillation of the resistor support; and

Fig. 9 is a horizontal section in the plane of the line 9—9 of Fig. 8.

10 Referring to the drawings and more particularly to Fig. 6, I there show a type of resistance element which the specific apparatus here disclosed has been designed to handle. It will be understood, however, that except for structural details, the apparatus is independent of the form of the resistor and may be rearranged to accommodate changes.

The resistance element shown in Fig. 6 is of the type described in my copending application Ser. No. 734,810 filed July 12, 1934, and a process for manufacturing which is disclosed in companion application Ser. No. 734,811 also filed July 12, 1934. The element comprises a ring of insulation 12 the outer periphery of which is coated 20 with a preferably graphitic resistance film 14 the ends of which contact with metallic terminals 16, which terminals are preferably carried around the edge of the unit to one face, as is indicated at 18. The annulus 12 has a keyway 20 which 30 properly orientates the same with respect to the terminals 16.

Referring now to Figs. 1, 2, and 3 of the drawings, the resistor 12 is mounted on a preferably rotatable support or table 22 in position to be operated on by either resistance lowering means 24 or resistance raising means 26, the actual resistance value being continuously indicated on a suitable ohm meter 28, and the means 24 or the means 26 being selectively and if necessary alternately used until the desired resistance value is accurately read on meter 28.

The resistance lowering means rubs and compacts the resistance film, and preferably takes the form of a rotatable wire brush, and I have discovered that, contrary to what might be anticipated, the abrasion of the resistance film by the wire bristles of such a brush does not raise the resistance by removing resistance material from the film, but rather lowers the resistance. 50 This strange result may be due to a compacting of the film which exceeds any effect caused by possible removal of some of the graphitic material.

The resistance raising device 26 rubs and partially removes the resistance film, and preferably takes the form of a rotatable cloth polishing wheel. The operation of such a wheel appears to be based on substantial removal of graphitic material, thereby thinning the film and raising 60 its resistance by an amount which far exceeds the effect of possible burnishing or compacting of the film by the wheel.

Both brush 24 and wheel 26 may be simultaneously driven by a single motor 30. Brush 24 and wheel 26 are preferably mounted at the ends 32 and 34 of a V-shaped frame, the apex 36 of which is oscillatable on an axis coinciding with the shaft 38 of driving motor 30. A handle 40 at the end 32 of the frame makes it readily possible to oscillate the frame from one side to the other, thereby bringing either the brush 24 or wheel 26 into rubbing engagement with the periphery of resistor 12.

The motor shaft 38 carries a pair of superposed 75 sprocket gears 42 and 44 which respectively drive

sprocket pinions 46 and 48 through chains 50 and 52. Pinion 46 is carried at the upper end of a vertical spindle 54, the lower end of which carries wire brush 24. Pinion 48 is secured to the upper end of a vertical spindle 56 which carries the cloth wheel 26 at its lower end. Brush 24 may be removed and replaced by loosening nut 58 and wheel 26 may be replaced by loosening nut 60. Brush 24 is preferably protectively housed by a shield 62 detachably secured to the bearing 64 by means of a set screw 66.

The V-frame comprises a main plate 68 which has depending bearings 64 and 70 formed integrally therewith, as well as the center bar of handle 40, and rearwardly projecting motion-limiting stop arms 72 and 74 best shown in Fig. 3. The stop arms are each fitted with adjustable stop screws 76 located for cooperation with a fixed stop pin 78. The motion-limiting mechanism is not essential, but is desirable to prevent a careless operator from applying excessive pressure on a resistor being treated.

The chain drive mechanism is enclosed and the V-frame completed by an upwardly dished sheet metal housing 80 having an outwardly turned bottom flange 82 secured to the main frame plate 68 by screws 84. It will be understood that because the axis of driving sprockets 42 and 44 coincides with the axis of oscillation of the frame, there is no change whatsoever in the relatively free frictionless drive of the brush and wheel regardless of the position of the frame. It will also be understood that a gear train or a belt drive may be used in lieu of the chain and sprocket drive shown, and that the axis of motor 30 may be displaced from its present location and geared or otherwise connected to the sprocket wheels 42 and 44, but the latter are preferably kept at the pivot of the frame as here illustrated.

The resistor 12 is mounted on a rotatable support 22 which is preferably driven by an independent motor 90 and in the present case motor 90 is mounted subjacent support 22 by means of bracket 92 and is connected directly thereto by a vertical shaft 94.

Referring now to Fig. 4, the support 22 comprises a sleeve 96 of insulation surrounding a metallic tube 98. Motor shaft 94 is received within tube 98 and is keyed to the assembly by a transverse pin 100. The upper end of sleeve 96 has fitted therein three metallic pins 102, 104 and 106 best shown in Figs. 4 and 5. Pins 102 and 104 are electrically connected to slip rings 108 and 110 fitted near the lower end of sleeve 96. Pin 106 is devoid of electrical connection and is employed primarily to provide a level three-point support for the resistor 12. A metallic collar 112 is fitted over the upper end of sleeve 96 in order to prevent wear when bringing the brush 24 or wheel 26 against the resistor. It will be understood of course that the overall diameter of sleeve 112 is less than the diameter of the resistor 12. It will also be realized from inspection of Figs. 5 and 6 that contacts 102 and 104 are properly located for engagement with the metallic terminals 18 of the resistor.

The slip rings 108 and 110 are contacted by suitable brushes 114 and 116 resiliently urged into engagement with the slip rings and electrically connected through conductors 118 and 120 to the ohmmeter 28 and associated energy source and circuits. The brushes are mounted in an insulation block 122, itself supported on a bearing plate 124 of the machine frame 126. The sleeve 96 may be provided with a collar 128 which prevents 75

the deposit on the slip rings of dirt and abraded material resulting from the operation of the machine.

The resistor 12 is readily applied to or removed from the support 22 by a clamp assembly comprising a pin 138 dimensioned to be received within tube 98 and carrying a handle 132 at its upper end and a transverse pin 134 near its lower end. Between the handle and pin are located a compression spring 136 and an upwardly dished clamp plate or cup 138. The top of tube 98 is cut to form diametrically opposed bayonet slots 140 best shown in Fig. 5. The side of tube 98 just above support 22 is fitted with a key 142 dimensioned to mate with the keyway 20 on the resistor 12. It will be understood that to mount resistor 12 in place it is merely necessary to slip the same over the upper end of tube 98 and to then apply the clamp assembly by means of handle 132 until pin 134 is anchored in bayonet slots 140, at which time spring 136 bears downwardly on cup 138 which in turn seats the resistor 12 accurately on the pins 102, 104 and 106, the resistor being held in proper register and being compelled to rotate by reason of key 142.

I have heretofore mentioned that the operation of adjusting the resistance may be combined with a burnishing of the film intended to stabilize the resistance to a value which normally would be attained only after initial period of use. For this purpose, I provide a burnishing shoe 144 best shown in Figs. 2 and 3, and oscillatably mounted on a block 146 secured at the upper end of a leaf spring 148, the lower end of which is attached to the insulation brush block 122, preferably by means including the lower end of an upstanding post 150 carrying an adjusting screw 152. This arrangement is clearly shown in Fig. 8 in which, however, the burnishing shoe 144 has been removed from block 146. It is manifest that during the resistance adjusting operation and while the resistor is being rotated by motor 98, the surface is being burnished by shoe 144, thus simulating the action of the contact shoe subsequently used in the complete resistance unit and thereby bringing the film to stabilized resistance value.

The apparatus as so far described is particularly satisfactory for use with uniform resistance elements. In some cases, however, the resistor is stepped or "tapered" in value. Specifically, the useful or resistance coated periphery of the element may be divided into, say four parts, each of which may have a different desired resistivity. In such case it is desirable to provide for separate adjustment of the resistance of the different sections for it may be necessary to change the resistance of one section but not of another section.

For this purpose, the resistor rotating motor 98 is de-energized and the resistor support 22 is treated as an oscillatable rather than a rotatable support. Shaft 94 has mounted thereon a wheel 154 which may be moved manually to position or oscillate support 22 as desired. As here illustrated, the wheel 154 may be a capstan wheel having radial holes 156 dimensioned to receive the inner end of an appropriate handle or capstan bar 158. The holes 156 are preferably disposed in suitable location relative to the key and contacts on the resistor support so that each capstan hole will correspond to one section of the stepped resistor. In operation it will be understood that with motor 98 de-energized, but motor 38 running, the capstan bar 158 is inserted in one

of the capstan holes and oscillated with one hand, while the resistance of the section being treated is adjusted while holding the handle 48 in the other hand. To treat another section it is merely necessary to move the capstan bar to another one of the capstan holes. 5

The meter provides a reading for only the overall resistance value and not for the individual sections. In practice I find that the most common variations in the units made from day to day result from changes in atmospheric conditions and other factors which affect the resistance of the sections upwardly or downwardly in a uniform manner. For this reason in most cases complete batches of stepped units may be treated exactly as though they were uniform units, i. e., they may be rotated under power on the support and the overall resistance adjusted to the desired value. The capstan mechanism for the support is desirable because once in a while, due to some error or because of first attempts to meet some new requirement, one section of complete batches of the units may run too high or too low in resistance value and it is only that section which needs to be treated. The necessary change in resistance of the section may be gauged by a similar change in the meter reading for the overall resistance. 20 25

In actual practice the procedure followed with stepped units is to select a few sample units from each batch. These units are treated uniformly to bring the overall resistance to desired value. They are then calibrated in a special fixture in order to obtain a reading for the individual resistance sections. As before stated, in most cases the sections have the desired value within permissible engineering tolerance. In such case, the batch is treated just like a uniform resistor. Occasionally, one section may have a resistance value too high or too low. In that case, the batch when first applied to the adjusting apparatus is treated with respect to the incorrect section, and if necessary is also treated as a uniform unit to obtain the desired overall reading. 30 35 40

Because of the foregoing, I prefer to control the motors 38 and 98 by the switching arrangement illustrated in Fig. 7, in which it will be seen that the brush motor 38 and the resistor motor 98 are both simultaneously energized or de-energized by a main control switch 168 provided that supplemental switch 162 is closed; but on the other hand, when switch 162 is open, motor 98 is dead and switch 168 controls only motor 38. These switches may be located as shown in Fig. 1. In fact, the operator need control only a single switch, namely switch 168, for when a batch of uniform resistors are being treated, the switch 168 is used to start and stop the apparatus including both motors, whereas when a batch of stepped resistors are being treated, the position of switch 162 is preliminarily changed, after which the operator manipulates switch 168 as a starting and stopping switch just as before. 45 50 55 60

The oscillation of the resistor support 22 for stepped units may be performed automatically under power instead of manually, and a slight modification for this purpose is illustrated in Figs. 8 and 9. In these figures, it will be observed that the shaft of motor 38 is extended below the motor housing and carries a worm 164 meshing with a worm gear 166 mounted at the inner end of a shaft 168 carried in a bearing pedestal 170 and having at its outer end a crank disc 172. The crank pin 174 is connected through suitable links 176 and 178 to one 70 75 76

end of a rocking bar or plate 180, the center bearing or hub 182 of which oscillates freely on motor shaft 94 and the opposite end 184 of which is turned upwardly and apertured at 186 in alignment with the capstan holes 156. A small capstan pin 188 is readily slipped through hole 186 into one of the capstan holes 156. When motor 30 is energized, the resistor is oscillated under power. When another section of the resistor is to be treated, it is merely necessary to retract capstan pin 188 and to thereupon reinsert the same in a different capstan hole.

It will be understood that when treating uniform resistors it is simply necessary to omit the use of the capstan pin 188, in which case the capstan wheel 154 rotates freely under the drive of motor 90 just as was described in connection with Figure 1.

The tips of the bristles of wire brush 24 bend somewhat and have a burnishing action. They have a tendency after long use to become excessively bent and this decreases the effectiveness of the brush. Instead of discarding the brush, it may be given renewed life by simply reversing the direction of rotation of the same. For this purpose, motor 30 is preferably made reversible, and I provide a switch 190 (see Fig. 1) for occasionally reversing the direction of rotation of the motor. Switch 190 is a double pole double throw switch connected in the conductors leading to the field of motor 30. The linear speed of the brush differs from that of the resistor, and no noticeable difference in operation results from reversal.

If desired, the same result may be obtained without using a reversing motor, by occasionally loosening nut 58 and removing and replacing brush 24 in reversed position. The switch is preferred for convenience because I find it desirable to reverse the direction of operation several times a day.

It is believed that the mode of constructing and using as well as the many advantages of my improved apparatus for adjusting the resistance value of resistors will be apparent from the foregoing detailed description thereof. The apparatus is relatively compact and inexpensive and is exceedingly convenient in use. The resistors may be brought to exact desired resistance value with extreme rapidity and ease by unskilled labor, because the large resistance meter dial directly in front of the operator accurately shows the resistance value and the V-frame is readily shifted to one side or the other as the indicator needle moves to one side or the other past the desired value (which of course is temporarily shown by a conspicuous mark) for any given batch of units being worked on. To the operator the sensation is exactly as though the movement of the handle is itself causing the indicator needle to move. The resistor is readily applied to and removed from the apparatus. During its treatment it is burnished to stabilize its resistance value. Non-uniform or stepped resistors may be treated as well as uniform resistors.

It will be apparent that while I have shown and described my invention in preferred form, many changes and modifications may be made in the structures disclosed without departing from the spirit of the invention defined in the following claims.

I claim:

1. Apparatus for adjusting the resistance value of a circular resistor, said apparatus comprising a support rotatable on a vertical axis for re-

ceiving and holding the resistor, a V-shaped frame oscillatable about a vertical axis displaced from the support, a wire brush rotatably mounted on one arm of said frame, a polishing or buffing wheel rotatably mounted on the other arm of said frame, motor means for driving said support, said brush and wheel, the driving connections to said brush and wheel being such that the brush and wheel are simultaneously driven during oscillation of the frame, said frame being so disposed with relation to said resistor support that oscillation of the frame in one direction brings the rotating brush into contact with the rotating resistor, while oscillation of the frame in opposite direction brings the rotating wheel in contact with the rotating resistor.

2. Apparatus for adjusting the resistance value of a circular resistor, said apparatus comprising a support rotatable on a vertical axis for receiving and holding the resistor, a frame oscillatable about a vertical axis displaced from the support, a wire brush rotatably mounted on one part of said frame, a cloth polishing or buffing wheel rotatably mounted on another part of said frame, a driving motor, driving connections between said motor and said brush and wheel, whereby the brush and wheel are simultaneously driven during oscillation of the frame, said frame being so disposed with relation to said resistor support that oscillation of the frame in one direction brings the rotating brush into rubbing contact with the resistor, while oscillation of the frame in opposite direction brings the rotating wheel into rubbing contact with the resistor, and a wheel on said support to facilitate oscillation of the support in order to rub a part only of the periphery of the resistor on the support.

3. Apparatus for adjusting the resistance value of a circular resistor, said apparatus comprising a support rotatable on a vertical axis for receiving and holding the resistor, an optionally usable motor beneath said support for rotating the same, a frame oscillatable about a vertical axis displaced from the support, a wheel rotatably mounted on one part of said frame for rubbing, compacting and lowering the resistance, a wheel rotatably mounted on another part of said frame for rubbing, partially removing and raising the resistance, a second driving motor, driving connections between said second motor and said wheels, whereby the wheels are simultaneously driven during oscillation of the frame, said frame being so disposed with relation to said resistor support that oscillation of the frame in one direction brings one of the rotating wheels into rubbing contact with the resistor, while oscillation of the frame in opposite direction brings the other rotating wheel into rubbing contact with the resistor, contacts on said support engaging the terminals of the resistor, a meter suitably connected through said contacts to indicate the resistance of the resistor, and a wheel on said resistor support to facilitate oscillation of the support in order to rub a part only of the periphery of the resistor on the support.

4. Apparatus for adjusting the resistance value of a circular resistor, said apparatus comprising a support rotatable on a vertical axis for receiving and holding the resistor, a motor beneath said support for rotating the same, a frame oscillatable about a vertical axis displaced from the support, a wire brush rotatably mounted on one part of said frame, a polishing or buffing wheel rotatably mounted on another part of said frame, a driving motor, driving connections between said

motor and said brush and wheel, whereby the brush and wheel are simultaneously driven during oscillation of the frame, said frame being so disposed with relation to said resistor that oscillation of the frame in one direction brings the rotating brush into contact with the resistor, while oscillation of the frame in opposite direction brings the rotating wheel in contact with the resistor, contacts on said support engaging the terminals of the resistor, a meter suitably connected through said contacts to indicate the resistance of the resistor, a switch controlling the energization of both motors, a second switch for de-energizing the resistor rotating motor, and means to facilitate oscillation of the support when the second switch is open.

5. Apparatus for adjusting the resistance value of a circular resistor, said apparatus comprising a rotatable support for receiving and holding the resistor, a frame oscillatable about an axis displaced from the support, a wire brush rotatably mounted on one arm of said frame, a cloth polishing or buffing wheel rotatably mounted on the other arm of said frame, a driving motor, driving connections between said motor and said brush and wheel, whereby the brush and wheel are simultaneously driven during oscillation of the frame, said frame being so disposed with relation to said resistor support that oscillation of the frame in one direction brings the rotating brush into rubbing contact with the resistor, while oscillation of the frame in opposite direction brings the rotating wheel into rubbing contact with the resistor, and power means geared to said motor for oscillating the support.

6. Apparatus for adjusting the resistance value of a circular resistor, said apparatus comprising a support rotatable on a vertical axis for receiving and holding the resistor, a frame oscillatable about a vertical axis displaced from the support, a wire brush rotatably mounted on one part of said frame, a polishing or buffing wheel rotatably mounted on another part of said frame, a driving motor, driving connections between said motor and said brush and wheel, whereby the brush and wheel are simultaneously driven during oscillation of the frame, said frame being so disposed with relation to said resistor support that oscillation of the frame in one direction brings the rotating brush into contact with the resistor, while oscillation of the frame in opposite direction brings the rotating wheel in contact with the resistor, a capstan wheel on said resistor rotating shaft, a capstan bar for oscillating the support, and power means geared to said motor for oscillating the capstan bar.

7. Apparatus for lowering the resistance value of carbonaceous film type resistors, said apparatus comprising means to support the resistor, a rotatable wire brush for rubbing and thereby compacting the resistance film, a motor for rotating said brush, means to cause relative movement of the brush and the resistor support whereby the resistor on the support may be rubbed by the wire brush, and means to reverse the direction of rotation of the wire brush whereby the direction of movement of the tips of the bristles may be changed after they have been too far bent to rapidly and efficiently burnish the surface of the resistance film.

8. Apparatus for adjusting the resistance value of a circular resistor, said apparatus comprising a rotatable support for receiving and holding the resistor, a frame mounted for movement in a direction transverse of the axis of rotation of the support, a wire brush rotatably mounted on said frame at one side of the support, a polishing or buffing wheel rotatably mounted on said frame at the opposite side of the support, motor means for driving said support, said brush, and said wheel, the driving connections to said brush and wheel being such that the brush and wheel are simultaneously driven during movement of the frame, said frame being so disposed with relation to said resistor support that movement of the frame in one direction brings the rotating brush into contact with the rotating resistor, while movement of the frame in the opposite direction brings the rotating wheel in contact with the rotating resistor.

9. Apparatus for adjusting the resistance value of a circular resistor, said apparatus comprising a rotatable support for receiving and holding the resistor, an optionally useable motor for rotating said support, a frame mounted for movement in a direction transverse of the axis of the support, a wheel rotatably mounted on one part of said frame for rubbing, compacting and lowering the resistance, a wheel rotatably mounted on another part of said frame for rubbing, partially removing and raising the resistance, a second driving motor, driving connections between said second motor and said wheels whereby the wheels are simultaneously driven during oscillation of the frame, said frame being so disposed with relation to said resistor support that movement of the frame in one direction brings one of the rotating wheels into rubbing contact with the resistor, while movement of the frame in opposite direction brings the other rotating wheel into rubbing contact with the resistor, contacts on said support engaging the terminals of the resistor, and a meter suitably connected through said contacts to indicate the resistance of the resistor.

HENRY G. RICHTER.
